UNITED STATES PATENT OFFICE.

OWEN OWENS, OF BERKLEY STATION, VIRGINIA.

PUZZLE.

1,413,186.

Specification of Letters Patent. Patented Apr. 18, 1922.

Application filed May 16, 1921. Serial No. 469,764.

To all whom it may concern:

Be it known that I, OWEN OWENS, a citizen of the United States of America, residing at Berkley Station, in the county of Norfolk and State of Virginia, have invented 5 certain new and useful Improvements in Puzzles, of which the following is a specification.

My present invention relates generally to 10 puzzles, my object being the provision of an entertaining puzzle whose solution while possible is sufficiently difficult to insure maximum amusement.

In the accompanying drawing which illustrates 15 my present invention and forms a part of this specification,

Figure 1 is a top plan view showing my improved puzzle,

Figure 2 is a vertical section taken there- 20 through, and

Figure 3 is a detail perspective view of one of the cages removed.

Referring now to these figures my improved puzzle consists of a board 10 of rec- 25 tangular form having upstanding side rails 11 entirely surrounding the same so as to enclose the playing or moving field on the upper surface of the board 10 and thus retain a series of balls 12 which are freely mov- 30 able over the playing surface of the board 10 and are prevented from displacement by a cover 13 of transparent material such as glass whose side edges are attached in any suitable manner to the upper edges of the 35 rails 11.

The upper playing surface of the board 10 is marked out to represent a baseball field having the representation of a diamond, with the players in the fielding positions 40 assumed in the progress of the game as well as representations of runners, the representation of the latter figures being preferably of a different color from those of the figures in the fielding positions. In the four cor- 45 ners of the diamond representative of the paths of the runners are traps 14 for the balls 12, and traps 15 and 16 similar to the traps 14 are also disposed on the playing field respectively in the center of the dia- 50 mond and in the catcher's position behind the corner of the diamond at which the bats- man takes his stand in line with the pitcher.

These several traps 14, 15 and 16 stand above the playing surface of the board 10

the latter of which is preferably flat 55 throughout except for the traps, and each trap is formed by a strip of material, preferably metal formed in V-shape with extensions converging toward one another so as to leave an open mouth 17 between their free 60 ends of slightly greater width than the diameter of the balls 12, each of these extensions 18 having one or more depending spurs 19 which may be driven into the playing surface of the board 10 in order to firmly 65 and permanently hold the traps in place.

In the manipulation of the device the object is to entrap the several freely rolling 70 balls 12 within the several traps 14, 15 and 16 and in order to make this solution of the puzzle amusing and difficult while yet possible of solution, I have resorted to a particular arrangement of the traps shown especially in Figure 1 where it will be seen that three of the corner traps 14 open in- 75 wardly toward the center of the diamond while the remaining corner trap 14 at the first baseman's position opens along a line paralleling a line connecting the second base- man's position with the batsman's position. 80 The trap 15 in the pitcher's position opens parallel to the last mentioned trap 14 and in the same direction that is toward the bats- man's position while the trap 16 in the catcher's position opens in an opposite direction 85 toward the trap 15.

By so constructing the traps and so dis- 90 posing them in relation to one another I have found it possible to create an amus- ingly difficult puzzle though one obviously 95 possible of solution by skillful tilting of the board 10. While I contemplate the puzzle will be sufficiently difficult of solution by permitting the balls to be shifted indiscrim- inately in the several traps, greater difficulty 95 may be brought about by coloring one of the balls one color to be trapped at the bats- man position with the two balls of another color for the traps 15 and 16 at the pitcher's and catcher's positions, the remaining balls 100 being uncolored for the remaining traps.

I claim:

A puzzle including a board having an upper flat surface marked out to represent a baseball field, balls freely rolling on the 105 said playing surface, and traps for the balls upstanding above the said playing surface and each having a single ball receiving open-

ing, said traps each including a strip of material upstanding edgewise from the playing surface of the board and of V-shape provided with extensions converging toward one another and with their free ends spaced apart to form between them the receiving mouth of the trap, said extensions having

depending spurs secured in the surface of the board to permanently hold the traps in place.

10

In testimony whereof I have affixed my signature.

OWEN OWENS.
